COLLAPSIBLE TABLE

Shin Obayashi, 41 W. 83rd St., New York, N.Y.

Filed Aug. 10, 1965, Ser. No. 86,524

Term of patent 14 years

(Cl. D33—14)

FIG. 1 is a side elevational view of a collapsible table showing my new design, in the open or extended position;

FIG. 2 is a top plan view thereof; and

FIG. 3 is a side elevational view of the table in the collapsed position.

I claim:

The ornamental design for a collapsible table, as shown.
